UNITED STATES PATENT OFFICE.

WILLIAM KELLY, OF MEMPHIS, TENNESSEE, ASSIGNOR OF FORTY-NINE ONE-HUNDREDTHS TO CHARLES M. WARNER, OF MEMPHIS, TENNESSEE.

DRAIN FOR WATER SYSTEMS.

1,216,815.

Specification of Letters Patent. Patented Feb. 20, 1917.

Application filed January 2, 1914. Serial No. 809,916.

To all whom it may concern:

Be it known that I, WILLIAM KELLY, a citizen of the United States, residing at Memphis, Shelby county, and State of Tennessee, have invented and discovered certain new and useful Improvements in Drains for Water Systems, of which the following is a specification.

My said invention consists in an improved form of drain adapted to be inserted in a pipe line leading to hydrants, or like places in water systems and has for its object to drain and collect the water remaining in the pipes above the point of connection, or above 15 the freezing point, when the water supply is turned off, whereby freezing and consequent damage to the system is avoided.

A further object is to provide means whereby the water collected in the drain device is forced out through the discharge pipe when the water is again turned on and the water collection receptacle thus emptied and made ready to receive the water drained from the pipe line when the supply is again 25 turned off.

Said invention consists further in the particular construction and arrangement of various parts whereby attachment may be readily made to hydrants and other parts 30 of water systems with which it is to be employed.

Referring to the accompanying drawings, which are made a part hereof and on which similar reference characters indicate similar 35 parts,

Figure 1 is a vertical section of my improved drain device as connected in a pipe line, and

Fig. 2 a vertical section through a device 40 showing a modified form.

Said improved drain device consists of a cup-shaped fitting or body A adapted to be connected in the water supply line 6 and having a discharge nipple 10 contracted in size from its connection with the pipe 6 to its upper end. The end of said nipple is exteriorly tapered from a point 9 to its point. A cap 3 is connected with the upper end of the body A by means of an internally 45 screw-threaded flange 4, which screws onto the upper end of said body A. Said cap is formed with a nozzle section extending both ways therefrom, the part 12 extending within the cap being formed with a cup-shaped 50 receiving end 11, and the part 13 extending

above the cap being formed with a discharge orifice 7 which tapers or increases in diameter gradually from its connection with the part 12 to its discharge end leading into the pipe 8, which leads to the hydrant, or other 60 discharge element for the water system.

Arranged alongside the body A and at a lower level than said body, is a drain receptacle 16. A pipe 17 leads nearly to the bottom of said receptacle 16 and is connected 65 by sections 14 and 15 with an aperture in the side of body A, the connection being at a point below the upper end of nozzle 10.

In operation, as will be readily understood, the force of the water discharging 70 from nozzle 10 into the orifice 7 through the receiving cup-shaped end 11 of said orifice will cause a suction through the pipe composed of the sections 14, 15, and 17, and will draw the water from the receptacle 16 and 75 also from the lower part 2 of receptacle A, surrounding said nozzle 10. The contraction of nozzle 10 will cause the water to be ejected therefrom under pressure and the expansion of the stream in passing through 80 the nozzle 7 will maintain said suction sufficient to keep these parts practically empty and create a partial vacuum therein. Immediately on turning the water off at the hydrant by a valve (not shown) in pipe 6, 85 the water remaining in pipe 8 and nozzle 7 will settle back into body A and through the pipe composed of the sections 14, 15, and 17 into the receptacle 16 below the freezing point indicated by the line a—a in Fig. 1. 90 On the water being again turned on the water is forced out of these receptacles, which are emptied and thus made ready again for draining the sections above the freezing point, as before.

In Fig. 2 is illustrated a slightly modified form whereby the same result is achieved, wherein the body and other connected portions are made in a single piece instead of in several parts as in Fig. 1. The nozzle 5^a 100 corresponds with the nozzle 10 in the principal construction, the body 1^a with the body A and cap 3 and parts formed thereon, and the pipe 15^a with the pipe composed of the sections 14, 15, and 17 in the principal construction. 105

The operation is the same as that of the principal construction, as will be readily understood.

Having thus fully described my said in- 110

vention, what I claim as new and desire to secure by Letters Patent is:

A drain device for pipe-lines of hydrants or the like comprising a receptacle interposed in said pipe-line below the freezing line and provided with a vacuum chamber, a conical nozzle formed integrally with said receptacle in communication with said pipe-line and connecting said receptacle on one side and projecting into the vacuum chamber, a cap screw-threaded on said receptacle and formed with a nozzle section extending in opposite directions, one part of said nozzle extending above the cap and formed with a discharge orifice of increasing diameter from its connection with the cap to its discharge outlet, and the other part of said nozzle extending within the cap and formed with a conical orifice extending

downwardly and partially inclosing said nozzle, a drain receptacle located adjacent the first named receptacle, and a drain pipe connected to communicate with said vacuum chamber and extending to a point adjacent the bottom of said drain receptacle, whereby the water drained from said pipe-line above the freezing line when said hydrant is out of use is siphoned back into the pipe-line, when the hydrant is again brought into use, substantially as set forth.

In witness whereof, I have hereunto set my hand and seal at Memphis, Tennessee, this 5th day of December, A. D. nineteen hundred and thirteen.

WILLIAM KELLY. [L. S.]

Witnesses:

JOHN W. FARLEY,
F. H. H. COLE.
